CLAIM

The ornamental design for a wire terminal as shown and described.

DESCRIPTION

FIG. 1 is a perspective view of a wire terminal showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line portion of the figure drawings is included to show portions of the wire terminal that form no part of the claimed design.
